BOTTLE CAP LIFTER

Fred H. Whiteley, Kansas City, Kans.

Application September 9, 1946, Serial No. 695,684

4 Claims. (Cl. 81—3.46)

1

This invention relates to tools for removing closures from the mouth of receptacles and particularly to the so-called "crown" type of caps for bottles, of the kind usually made of tinned iron or other suitable material and having a corrugated edge or annular skirt that is crimped over the mouth of the bottle in a manner well known in the art.

It is well known that most bottles now in use to contain carbonated beverages particularly, have an annular bead or continuous annular, external shoulder formed thereon, at the neck and near the open mouth thereof, and that this shoulder is spaced from the inner edge of the skirt of the crown cap when the same is applied to the bottle and crimped in place. It is the primary object of this invention to provide a bottle cap remover especially adapted for use on bottles constructed in the aforesaid manner.

An important object of this invention is to provide a bottle cap remover having a body provided with a portion engageable with the shoulder of a bottle, formed to present a fulcrum; and a portion disposed between the cap and the shoulder, engageable with the inner edge of the cap to dislodge the same as force is applied to one end of the body and as the fulcrum rests on the shoulder of the bottle.

More specifically, this invention provides a bottle cap remover in the nature of a body formed from an initially flat sheet of material and having a slot formed therein of a size permitting the same to be moved over the cap into operative position where a portion of the walls forming the slot is disposed between the cap and the bottle shoulder, and having a pair of inwardly extending salients or ears to present a fulcrum on the shoulder as the remover is moved inwardly toward the bottle for dislodging the cap.

Other objects of this invention include the specific manner of forming the bottle cap remover, the manner of forming the slotted portion thereof to present clearance as the same is moved about the bottle shoulder, and the manner in which the remover is associated with the conventional elements of the well-known crown caps and the shouldered bottle, all of which specific objects will be made clear or become apparent during the course of the following specification, referring to the accompanying drawing, wherein:

Fig. 1 is a top plan view of a bottle cap remover made in accordance with my present invention, illustrating a bottle cap and the neck of a bottle in dotted lines, in association with the remover.

Fig. 2 is a side elevational view of a portion of the neck of a bottle and the remover shown in Fig. 1.

Fig. 3 is a top plan view of a bottle cap remover illustrating a modified form thereof; and

Fig. 4 is a side elevational view of the remover

2

illustrated in Fig. 3, showing the same in association with a portion of a bottle neck and the cap.

It is possible to embody the instant invention in bottle cap removers having a large number of forms, and therefore, two ways of constructing the remover are herewith illustrated.

In Figs. 1 and 2, the closure is in the form of a conventional crown cap, broadly designated by the numeral 10, having as a component part 10 thereof, a depending skirt 14 extending laterally from the upper face thereof, that clampingly engages the sides of a bottle 16 when in operative position. As is well known in the art, the skirt 14 of cap 10 is crimped through the employment of a die and forced tightly against the bottle near the mouth thereof.

The bottle 16 chosen for illustration, has a continuous, external, annular bead or shoulder 18 at the neck thereof and near its open mouth.

20 This type of bottle is now well known in the art, and is the most commonly used bottle on the market, particularly for such liquids as carbonated beverages, soft drinks of all kinds, and many kinds of alcoholic beverages. This shoulder is spaced from the uppermost edge of the bottle 16 forming the open mouth thereof and the upper edge thereof is spaced from the lower edge of skirt 14 when cap 10 is in place.

25 The cap remover constituting the subject matter of this invention is designed to be inserted in this space between skirt 14 and shoulder 18, comprises a body broadly designated by the numeral 20. This body 20 is formed by stamping the same from an initially flat sheet of material, 30 the thickness whereof is preferably the same as the distance between the lower edge of skirt 14 and the upper edge of shoulder 18 for more effective operation of the remover.

35 When formed as illustrated in Fig. 1, body 20 has a handle portion or grip 22 at one end thereof, and is provided with an elongated slot or opening 24 extending from grip 22 to a point near the opposite end of body 20. A fulcrum is established by a pair of salients or ears 26 spaced from this opposite end of body 20, which salients 26 extend inwardly into the slot 24 in substantially diametrically opposed relation.

40 A cap engaging portion 28 is arcuate to conform with the contour of skirt 14. This portion 45 forms said opposite end of body 20 and joins the salients 26. Portion 28 also forms a part of the walls of body 20 which defines slot 24 and merges into the salients 26 as the end of slot 24 adjacent to grip 22 is approached.

45 The distance across slot 24 adjacent to salients 26 and opposed to the portion 28 is greater than the diameter of the cap 10, permitting the 50 remover to be slipped over the cap 10 to operative position. After such movement, the operator slips the remover laterally until portion 28

underlies a portion of skirt 14 and salients 26 rest on shoulder 18. It is clear therefore, as inward pressure is exerted on grip 22, an outward force will be applied to the cap 10 until the same is dislodged.

It is notable also that that portion of slot 24 between salients 26 and grip 22 is also wide enough to clear shoulder 18 as grip 22 is moved inwardly, thereby preventing the remover from slipping laterally on shoulder 18 to a point where portion 28 is out of engagement with skirt 14.

In the form shown in Figs. 3 and 4, a body 50 has a grip 52, from which projects a pair of fingers 54, forming a slot 56. Fingers 54 terminate in a pair of spaced-apart ends 58 to form a cap engaging portion, the distance therebetween being less than the diameter of both the skirt 60 of a cap 62, and the diameter of shoulder 64 of bottle 66. In other words, the ends 58 of fingers 54 are spaced-apart a distance slightly greater than the diameter of that part of the neck of bottle 66 between cap 62 and the shoulder 64 to permit the same to partially circumscribe the bottle when in operative position.

As in the type of remover described and shown in Figs. 1 and 2, body 50 has a pair of inwardly extending salients 68, the distance therebetween in this case however, being less than the diameter of bottle 66 above shoulder 64. Thus, as the remover is moved to operative position, salients 68 serve not only as a fulcrum to facilitate the prying action against cap 62, but limit movement of the fingers 54 around bottle 66. As grip 52 is moved inwardly toward bottle 66, slot 56 will clear shoulder 64, since here again, the width of slot 56 between salients 68 and grip 52 is greater than the diameter of shoulder 64.

When either of the two forms of my invention is employed in the manner herein described, the crown cap is easily removed from the bottle with a minimum of pressure on the grip end of the remover because of the fulcrum established by the inwardly extending salients, and no damage is caused to the cap. Thus, the cap may be reused to close the bottle by simply pressing the same into place, whereby any contents remaining in the bottle will be sealed against entering air, substantially as effectively as is true on first use of the cap.

Having thus described my invention, what I claim as new and desire to secure by Letters Patent is:

1. A cap remover for bottles having an annular, external shoulder adjacent the mouth thereof and wherein the shoulder is in opposed, spaced relation with the inner edge of the cap, said remover comprising a body having a grip at one end thereof; a fulcrum spaced inwardly from the opposite end of the body and formed to rest upon the shoulder when in an operative position; and a portion at the said opposite end of the body disposed beneath the inner edge of the cap when the fulcrum is resting on said shoulder, whereby dislodging outward force is applied to the cap when inward pressure is exerted upon the said grip, said fulcrum including a pair of substantially diametrically opposed salients having the cap engaging portion between the proximal end of the body and the salients, the distance between said salients being greater than the diameter of that portion of the bottle between the cap and said shoulder.

2. A cap remover for bottles having an annular,

external shoulder adjacent the mouth thereof and wherein the shoulder is in opposed, spaced relation with the inner edge of the cap, said remover comprising a body having a grip at one end thereof; a fulcrum spaced inwardly from the opposite end of the body and formed to rest upon the shoulder when in an operative position; and a portion at the said opposite end of the body disposed beneath the inner edge of the cap when the fulcrum is resting on said shoulder, whereby dislodging outward force is applied to the cap when inward pressure is exerted upon the said grip, said body having a slot formed therein, said fulcrum including a pair of opposed salients extending inwardly into said slot, said cap engaging portion forming a part of the walls of said slot adjacent said salients.

3. A cap remover for bottles having an annular, external shoulder adjacent the mouth thereof and wherein the shoulder is in opposed, spaced relation with the inner edge of the cap, said remover comprising a body having a grip at one end thereof; a fulcrum spaced inwardly from the opposite end of the body and formed to rest upon the shoulder when in an operative position; and a portion at the said opposite end of the body disposed beneath the inner edge of the cap when the fulcrum is resting on said shoulder, whereby dislodging outward force is applied to the cap when inward pressure is exerted upon the said grip, said body having a slot formed therein, said fulcrum including a pair of opposed salients extending inwardly into said slot, the width of a portion of said slot disposed inwardly from said salients being wider than the diameter of said shoulder whereby the body partially circumscribes the shoulder when inward pressure is exerted upon the grip.

4. A cap remover for bottles having an annular, external shoulder adjacent the mouth thereof and wherein the shoulder is in opposed, spaced relation with the inner edge of the cap, said remover comprising a body having a grip at one end thereof and an elongated slot spaced inwardly from the opposite end thereof, that portion of the body forming one end of the slot adjacent said opposite end of the body being arcuate and disposed beneath the inner edge of the cap when in an operative position, said arcuate portion terminating in a pair of opposed salients intermediate the ends of said slot, the distance between said salients being less than the diameter of said shoulder to form a fulcrum resting on said shoulder when the said arcuate portion is the operative position, whereby dislodging outward force is applied to the cap when inward pressure is exerted upon the said grip.
